UNITED STATES PATENT OFFICE.

ERNEST C. MORIARTY, OF WASHINGTON, DISTRICT OF COLUMBIA.

PROJECTILE.

Application filed April 9, 1924. Serial No. 705,374.

To all whom it may concern:

Be it known that I, ERNEST C. MORIARTY, a citizen of the United States, residing at Washington, District of Columbia, have invented new and useful Improvements in Projectiles, of which the following is a specification.

This invention relates to projectiles and more particularly to relatively large armor 10 piercing navy projectiles especially adapted for use in high angle fire.

As is well known to those familiar with the art, navy projectiles of the larger caliber are usually fired at long range and high 15 angle of elevation and when they strike the target such as a relatively thick armor plate there is probably a large oblique angle between the trajectory of the projectile and the armor plate causing the projectile to 20 turn on its axis at the moment of impact. Such turning movement causes the rear end of the projectile to be subjected to a heavy side blow frequently tearing off the rear end or heel of the base. If this tearing action 25 extends into the cavity of the projectile containing the explosive charge then the explosion does not have an equal efficiency.

It is, therefore, one of the objects of the present invention to construct an armor 30 piercing projectile of the above character adapted to avoid this primary objection whereby a fracture takes place at the base. It will occur along certain predetermined 35 lines thereby maintaining the walls of the cavity substantially intact so far as the effectiveness of the subsequent explosion is concerned.

A further object is to provide a projectile 40 of the above character which may be relatively inexpensively manufactured and assembled.

Other objects will be in part obvious to those skilled in this art and in part herein-after pointed out in connection with the accompanying sheet of drawings illustrating 45 one of the various possible embodiments of the invention.

This drawing illustrates a portion of the rear end of an armor piercing projectile.

Referring now to this drawing in detail, 50 1 indicates the rear wall portion of the projectile which terminates at the forward or right hand end as viewed in the usual ogival point and 2 denotes the cavity adapted to be 55 filled with high explosive. This cavity is closed by a base plug 3 and the outer wall

of the projectile is provided with a rotating band 4. These parts being all of standard construction it is believed to be unnecessary to go into the same more in detail.

The invention as herein disclosed consists in the provision of a cut in the base of the projectile which is carried forward to a point corresponding to approximately the center of the rotating band although it may extend more or less if desired. This is preferably filled with a relatively soft metal 5 such as lead or copper although it is conceivable that other materials might be used such as cement. Just forward of the filling 5 is a circumferential, shallow, narrow cut 6 and a second under-cut portion 7 is preferably located above the filler 5 and near the rear of the rotating band 4. The filling 5 is also held in place by a rotatable threaded band 8. These cuts or weakened portions tend to indicate the weakened line along which fracture will take place as the projectile passes through the armor at an angle. The cuts being small will not in any 80 way interfere with or lessen the transmission of the torque exerted on the rotating band to the projectile body. In operation when the projectile is fired and strikes the armor plate at an angle there will be a 85 force exerted upon the rotating band inward and towards the rear of the projectile. The inward component tends to compress the filler and the rearward component will come directly on the weakened section at 90 the rotating rear of the band groove. The force corresponding to the pressure of the filler will be added to the direct force due to the rear component of the blow on the band 4 with the result that the heel of the 95 projectile will be broken thereby releasing the ring and rotating band without in any way materially weakening the walls of the explosive cavity 2. As soon as the heel is broken away the inward component of the 100 blow on the band will compress the unsupported filler with the result that the projectile will break between the end of the cut 7 in the base and the forward cut 6 in the band score. Lead is preferably used 105 because it is easily compressed and it will be seen that the force which tends to break off the heel is almost independent of the direction of the blow on the band as the lead acts similar to a fluid which transmits 110 its pressure in all directions.

It is thus seen that the present invention

comprises a simple, practical, reliable and efficient means for avoiding the objection heretofore experienced with armor piercing projectiles striking the target at a relatively 5 large angle. The heel of the projectile is torn away deformed or yields on well-defined lines without in any way materially weakening or affecting the walls of the main explosive charge.

10 What I claim is:—

1. In a projectile of the character described having a high explosive chamber and a base plug, the rear of said projectile being provided with an annular groove extending forwardly beneath the rotating band and provided with a filler whereby when the projectile strikes a target at an oblique angle subjecting the rear of the projectile to a side blow the heel will yield 20 without materially affecting the walls of the explosive chamber.

2. In a projectile of the character described having an explosive chamber and a base plug, the wall of said projectile being 25 provided at its rear with an annular concentric groove, a filler in said groove, means for holding said filler in place, said filler groove extending forwardly beneath the rotating band of the projectile whereby when 30 the projectile strikes at an oblique angle to subject the rear thereof to a side blow, the heel of the projectile will yield along said groove and closing means.

3. In a projectile of the character described having an explosive cavity, a base 35 plug and a rotating band, a concentrically disposed annular groove in the base extending forwardly beneath the rotating band, a metallic filler for said groove and a threaded ring for holding said filler in place 40 whereby the heel of said projectile will yield when the projectile strikes a target at an angle sufficient to subject the heel to a side blow for the purpose of avoiding 45 a material weakening of the walls of the explosive chamber.

4. In a projectile of the character described having an explosive cavity, a base 50 plug and a rotating band, a concentrically disposed annular groove in the base extending forwardly beneath the rotating band, a metallic filler for said groove, a threaded ring for holding said filler in place whereby the heel of said projectile will be turned 55 away when the projectile strikes a target at an angle sufficient to subject the heel to a side blow for the purpose of avoiding a material weakening of the walls of the ex-

plosive chamber, the heel of said projectile being provided with a weakening groove adjacent the filler groove thereby to direct the fracture along certain predetermined lines.

5. In a projectile of the character described having an explosive cavity, a base plug and a rotating band, a concentrically disposed annular groove in the base extending forwardly beneath the rotating band, a metallic filler for said groove, a threaded ring for holding said filler in place whereby the heel of said projectile will be turned away when the projectile strikes a target at an angle sufficient to subject the heel to a side blow for the purpose of avoiding a material weakening of the walls of the explosive chamber, the heel of said projectile being provided with a weakening groove adjacent the filler groove thereby to direct the fracture along certain predetermined lines, said grooves extending upwardly from the rear of the filler cavity.

6. In a projectile of the character described having an explosive chamber, a rotating band and a base plug, a cavity concentrically disposed with respect to the base plug and extending under the rotating band, a threaded ring adapted to be screwed into the base of the projectile to close the cavity, a metal filler for said cavity and weakening grooves adapted to direct the line of fracture when the heel of the projectile is subjected to a side blow, one of said grooves extending upwardly from the rear of the cavity and the other of said grooves extending downwardly from the rotating band.

7. An armor piercing projectile having an internal cavity for explosive, a base plug and a driving band groove, wherein the base end portion of the projectile is provided with a deep annular groove concentric with the axis of the projectile, the outer surface of said groove being of cylindrical shape and the inner surface of conical shape.

8. An armor piercing projectile having an internal cavity for explosive, a base plug and a driving band groove, wherein the base end portion of the projectile is provided with a deep annular groove concentric with the axis of the projectile and extending forwardly to underlie the driving band groove, and a supporting sleeve located within said annular groove.

Signed at Washington, District of Columbia, this 28th day of February, 1924.

ERNEST C. MORIARTY.
